W. W. CAMPBELL

DRY STEAM SLEEVE FINISHING BOARD

Filed July 30, 1926

UNITED STATES PATENT OFFICE.

WALLACE W. CAMPBELL, OF DENVER, COLORADO.

DRY-STEAM SLEEVE-FINISHING BOARD.

Application filed July 30, 1926. Serial No. 125,926.

This invention relates to improvements in dry steam finishing boards for sleeves of the type shown and described in my Patent No. 1,592,655, July 13, 1926.

5 In devices of the type to which this invention relates, it has been found that on account of the fact that so many garments are provided with sleeves having fur trimmings that it becomes quite necessary to 10 provide special means for protecting the fur against injury from the steam during the finishing process. It is therefore an object of this invention to provide a machine of the type disclosed in my patent with a protecting 15 means for guarding against the injurious effects of the steam on the fur trimming. In my patented device I have shown a filtering device provided in the outlet so that there will always be a water seal that 20 provides resistance against the exit of the steam. I have found from experience that although this filtering device is quite successful in its operation, better results can be obtained if, in addition thereto, the apparatus 25 is provided with a valve and a pipe connection that permits the steam to escape freely without passing through the filtering device. The reason for this is that when no steam is desired to pass through the 30 cylindrical member that is intended to be inserted into the sleeves, the valve to which reference has just been made can be opened, thereby permitting the steam to escape freely. Another object of this invention is to 35 provide the perforated tubular arm with a padding which will give an even distribution of the steam and which will protect the silk lining against injury from the hot steam. This padding also permits the use of irons 40 for smoothing purposes and protects the garment from injury which would be caused by coming in contact with the metal.

The above and other objects which will appear as the description proceeds are obtained by means of a construction and arrangement of parts which will now be described in detail, reference for this purpose being had to the accompanying drawing in which the preferred embodiment of the invention has been shown, and in which:

Figure 1 is a side elevation of the steam finishing board with parts broken away to better disclose the construction;

Figure 2 is a section taken on line 2--2, 55 Figure 1;

Figure 3 is a section through the valve taken on line 3--3, Figure 2;

Figure 4 is a section taken on line 4--4, Figure 2;

Figure 5 is a view partly in elevation and partly in section taken on line 5--5, Figure 1; and

Figure 6 is a section taken on line 6--6, Figure 1.

Numeral 1 designates the floor or other supporting surface upon which the device is placed. The device itself consists of supporting pipe 2 whose lower end is provided with a flange coupling member 3 that is adapted to be secured to the floor by means 65 of lag screws or bolts 4. Pipe 2 is made in two sections which are connected by means of a T 5. Secured to the side opening in the T member is a pipe 6 which is connected by means of an L 7 to the downwardly extending pipe 8 whose lower end is secured to the floor by means of screws 9 that pass through the flange 10. The upper end of the upper section of pipe 2 is closed by means of a plug 11 (Figure 4) and has attached to it a T 12 which forms part of the assembly of the finishing board.

The finishing board consists of a tubular member 13 whose upper surface has been flattened in the manner indicated at 14 in Figure 6. The upper flattened surface is provided with a plurality of small openings 15 through which the steam may escape. The outer end of member 13 is closed by means of a plug 16. The inner end of member 13 is connected to a cross 17. A pipe 18 is threadedly connected to the lower opening in the cross 17 and with the upper opening in the T 12. Secured to the upper opening of the cross 17 is a plug 19 to the upper end of which a flange coupling 20 is connected. A shelf or support 21 is secured to the coupling 20 so as to form a convenient place for holding brushes or other implements that are used in the steaming and pressing operation. A steam pipe 22 is connected with a control valve 23. From this valve a pipe 24 extends to the reducing T 25, from which a short pipe 26 extends to the outer end of the cross 17. A section of pipe which has been indicated by numeral 27 extends from the T 25 to the T 28. The T 28 is connected with the T 12 by means of two short pipe sections 29 and a coupling 30. From the lower opening in T 28 a pipe 31 extends 105

110

downwardly and is connected with the **T** 32, from the side of which a pipe 33 extends to the gate valve 34. From the other side of the gate valve a pipe 35 extends and is connected with an exhaust pipe 36 by means of an **L** 37. The valve 34 is of an ordinary and well known construction but has been shown in section in Figure 3 in which a gate 38 is pivoted to oscillate about an axis 39 to the outer end of which a handle 40 is connected. When the gate 38 occupies the position shown in Figure 3, the valve is closed, but if the handle 40 is moved downwardly, the gate will be moved upwardly into the curved chamber 41 so as to open the valve. A spring 42 has its lower end connected with the outer end of the lever 40 and its upper end connected to the shelf 21. This spring is normally under tension and keeps the valve 34 in closed position. For the purpose of opening the valve 34 against the action of the spring, I have provided a pedal 43 which has one end pivoted at 44 to a stationary bracket 45. The free end of this pedal is connected to the outer end of lever 40 by means of a wire or rod 46. When the operator places his foot on the pedal 43 and exerts a downward pressure thereon, the valve 34 will be moved to open position, thereby permitting the free escape of steam from the pipes. Surrounding the tubular member 13 is a pad 47 which serves to distribute the steam so as to cause a uniform action on the material that is being steamed and pressed. A sleeve 48 of fiber, hard rubber or some similar substance is slipped over the padding 47 and serves to protect the fur trimming at the end of the sleeve. This fiber sleeve may, of course, be omitted when the article which is being steamed has no fur trimming. In order to provide a convenient support for the fiber sleeve 48, I have made the pipe 24 in two sections which are connected by means of a **T** 49. An **L** 50 is connected to the side opening of this **T** and a pipe 51 extends vertically from the open end of the **L** 50. The upper end of pipe 51 is closed by means of a cap 52. This forms a very convenient support for the fiber sleeve, which when not in use occupies the position shown in Figure 2. Extending downwardly from the **T** 32 is a pipe 53 to the lower end of which a reducing coupling 54 is secured. The smaller end of this reducing coupling is threadedly connected to a coupling 55 to whose lower end the exhaust pipe 56 is secured. Screens 57 are placed at the lower end of the couplings 54 and at the upper end of the pipe 56 and between these screens filter material 58 is placed. This forms an arrangement which tends to collect the water condensed from the steam and to form a water seal which will permit the water to filter through slowly.

The parts 53 to 57 may be omitted if desired and the pipe 53 replaced by a plug which closes the lower end of the **T** 32.

Having one end threadedly connected with the threaded axial opening in member 58 so as to be in communication with the interior of pipe 26 is a pipe 59 which extends into the interior of the arm 13 and terminates in a cap 60 near the plug 16. A smaller pipe 61 has one end connected with the cap 60 (which has an opening that provides a passageway between pipes 59 and 61) and has its other end provided with an **L** 62 to the other end of which a pipe section 63 extends downwardly into the pipe 18. It is now evident that the high pressure steam from pipe 24 must flow through pipes 26, 59, 61 and 63 before it can enter the interior of the arm 13. It will also be noted that the steam that leaves pipe 63 does so in a downward direction. This tends, first, to direct any condensed steam into pipe 18 and, second, to produce a suction, due to the injector action, which tends to remove any steam and moisture from the arm 13. When the valve 34 is wide open steam will flow freely from pipe 63 and the suction produced will immediately remove all steam from the interior of arm 13. The pipes 59 and 61 also serve as heaters to keep the steam dry.

Let us assume that the pipe 22 is connected to a source of steam under suitable pressure and that the valve 34 is open. When the valve 23 is open steam will flow from pipe 22 through pipes 24, 27, 33 and valve 34 to the exhaust pipe 36. Some steam will also flow through pipes 26, 59, 61 and 63 and thence through pipes 18, 29, 31 and 33 to valve 34. If we now close the valve 34, the steam will have no way of escape except through the openings 15 in the tubular member 13. When the parts 53 to 57 are in place, there will be a slow escape of steam through the filter, but water will soon accumulate at the filter, so as to permit only a small amount of steam to escape. It is now evident that when it is desired to have steam emerge from the openings 15, the operator merely removes the pressure from the pedal 43, thereby allowing the valve 34 to close. Steam will then pass through pipes 26, 59, 61 and 63 into the interior of tubular member 13. If any moisture is contained in this steam when it leaves pipe 63, this will pass downwardly into the pipe 18, thereby permitting only dry steam to enter the member 13. Any water that condenses in member 13 flows downwardly through pipe 18 from which it finally enters the pipe 36 or the pipe 56 and in this manner no water of condensation will flow outwardly through the openings 15. The rate at which steam may enter the apparatus is controlled by means of the valve 23 and the flow of steam through the openings 15 is controlled by the pedal operated

valve 34 in the manner above described. When the device is in use, the member 13 is introduced into a sleeve and pressure on the pedal 43 is released, thereby permitting 5 steam to flow outwardly and to act upon the sleeve that is being steamed. The flattened upper surface of the tubular member 13 and the padding 17 make it possible to employ irons for smoothing the material.

10 I want to call particular attention to the fact that I have two separate means for removing the water of condensation from the steam so as to assure that only dry steam will pass through the openings 15. One of 15 these means comprises the pipes 24 and 27 together with the T 25, this arrangement making it necessary for the dry steam to make a right angle turn in order to enter the pipe 26 and this causing the water of condensation to become separated from the steam at this point. The downward direction in which the steam issues from pipe 63 where it enters pipe 18 forms the second 20 separating means which takes care of the water of condensation that is formed in the 25 pipes and also serves to remove water from the interior of members 13. I want to call particular attention to the fact that the parts indicated by numerals 53 to 57 can be dispensed with in the present embodiment, although the construction shown in Figure 5 is considered to be preferable to a construction in which these parts were omitted.

Having now described the invention what 30 is claimed as new is:

1. In a sleeve steaming board having a 35 perforated, tubular arm, means for supporting said arm in a horizontal position, one end of said arm being closed, and means for 40 connecting the other end of the arm with a source of steam under pressure and with an exhaust pipe, the combination with said ex-

haust pipe of a valve having means comprising a spring for holding it in closed position and means comprising a pedal for 45 moving it to open position when pressure is applied to the pedal.

2. In a sleeve steaming board having a 50 perforated, tubular arm, means for supporting said arm in a horizontal position, one end of said arm being closed, and means for connecting the other end of the arm with a source of steam under pressure and with an exhaust pipe, the combination with said 55 exhaust pipe of a valve having means comprising a spring for holding it in closed position and a filter adapted to collect water so as to form a water seal, said valve and filter being in parallel passages.

3. In a sleeve steaming board having a 60 perforated tubular arm, a fibrous pad enclosing said arm and means for supplying live steam to the interior of said arm, an impervious tubular section adapted to be put into place over the arm so as to surround the 65 arm and pad and to serve as a protector for material that is to be guarded against the effect of the steam.

4. A sleeve steaming board having a 70 perforated tubular arm, means for supporting said arm in horizontal position, one end of said arm being closed and the other open, means for connecting the open end of said arm with a source of steam under pressure and an exhaust pipe in connection with said 75 arm, a pipe extending through the interior of the arm and having one end in communication with the steam supply and the other end opening into the exhaust pipe whereby the steam as it flows through the pipe will 80 diminish condensation.

In testimony whereof I affix my signature.
WALLACE W. CAMPBELL.
